UNITED STATES PATENT OFFICE.

FREDERICK GANDY, OF CINCINNATI, OHIO.

SMOKE-BOX FOR LOCOMOTIVES.

SPECIFICATION forming part of Letters Patent No. 409,033, dated August 13, 1889.

Application filed November 1, 1888. Serial No. 289,700. (No model.)

To all whom it may concern:

Be it known that I, FREDERICK GANDY, a subject of the Queen of Great Britain, and a resident of Cincinnati, in the county of Hamilton and State of Ohio, have invented certain new and useful Improvements in Smoke-Boxes for Locomotives, of which the following is a specification.

My invention has for its object to provide a locomotive smoke-box having air-inlets for the admission of air to assist in the combustion of cinders and two concentric exhaust-pipes communicating with the engine-cylinders and having separate and independent nozzles, which terminate in open mouths on the same horizontal plane for the purpose of maintaining a uniform draft, relieving the engine of back-pressure, and promoting a perfect combustion of the cinders, so that they will not gain access to the smoke-stack.

Figure 1 is a longitudinal vertical section of a locomotive smoke-box and boiler with my improvements attached. Fig. 2 is a transverse section on line $\alpha\alpha$, Fig. 1. Fig. 3 is a transverse section on line yy , Fig. 1. Fig. 4 is a central vertical section of my improved exhaust-pipes and nozzle. Fig. 5 is a central transverse section of Fig. 4. Fig. 6 is a horizontal cross-section on line bb , Fig. 5. Fig. 7 is a similar section on line aa , Fig. 5. Fig. 8 is a section on line cc , Fig. 5.

1 represents the shell of an ordinary boiler, 2 tubular flues, and 3 the dry-steam feed-pipe projecting into the smoke-box 4. 5 represents 35 the steam-pipe divided into two branches 5', which pass down through the smoke-box for conveying steam to the steam chest and cylinders. These parts are of the ordinary construction.

40 In the accompanying drawings, 6 represents the base or cylinder saddle of the exhaust and steam pipes for supporting the same directly at the base of the smoke-box.

45 7 represents the interior exhaust-pipe connected by a suitable passage 8 to one of the cylinders.

9 represents the exterior pipe connected by passage 10 to the opposite cylinder. The nozzles I have shown constructed of a separate 50 piece from the exhaust-pipes, provided with flanges 12, resting on flanges 13 on the top of

said concentric pipes. This is merely for convenience of adjusting different-sized nozzles.

23 represents ribs. They are placed between the two pipes or passages of the nozzles 55 for stiffening the same and holding the inner pipe in position.

In the present instance I have shown hollow stay-bolts 14, provided with air-orifices 15, passing centrally through said stay-bolts. 60 These I provide at the bottom portion of the smoke-box, as shown by the dotted center, Fig. 1. Any desired number of apertures may be employed to suit varied engine-services, and different forms of apertures may 65 be employed for admitting the air into the smoke-box for burning up the cinders; but I deem this form the best. The stay-bolts perform another office. Were the cinders burned by the admission of air into a smoke-box of 70 ordinary construction, it would become unduly heated and burn out. This I avoid by a water-jacket, which also suitably heats the feed-water. This jacket-space 16 is formed by the shell 17 concentrically within the shell 75 18. The stay-bolts 14 and 28 support the two shells and form a water-heating space.

19 represents the feed-pipe from injector or pump with check-valve 30, with its inner orifice terminating within jacket 16. In order 80 to purify the water and take pure water into the boiler, I provide feed-pipes 20, which tap the top of the jacket-space 16 and connect with the bottom of the boiler below the flue-tubes 2, by which means I accomplish two results: first, the pure water is taken from the jacket 16 and supplied to the boiler and allows the clearing or settling of the water, the impurities passing down into the mud-drum 21, which connects with the bottom of the 85 jacket 16, as shown in Figs. 1 and 3.

22 represents a blow-off cock for blowing out the impurities which accumulate in the mud-drum 21 or bottom of the heating-space. The draft from the furnace and the consuming 95 of cinders or carbon within the smoke-box will heat the feed-water and materially aid in purifying the same.

An important function is performed by the concentric exhaust-pipes in connection with 100 the smoke-box air-inlets—namely, in maintaining a steady and uniform draft, while the

cinders are consumed with the assistance of the air admitted through the orifices in the periphery of the smoke-box. If the mouths of these pipes are not on the same plane, one will 5 cause a back-pressure on the engine with which the other communicates, and the draft will not be continuous and uniform, and if the air-inlets are dispensed with there will not be a perfect combustion of the cinders, nor will 10 the draft be so free and steady as when the air-inlets and concentric exhaust-pipes are both employed.

In order that the smoke-box may be cleaned, I provide a cap 24, covering a man-hole at the 15 bottom of the box, which may be removed for that purpose. 25 represents a separate man-hole for giving access to the center portion of the fire-box. It is sometimes desirable to 20 cover the inside of the smoke-box with a non-conductor of heat—such as fire-clay, asbestos, &c.—as indicated by dotted lines 26, Fig. 1; but ordinarily such non-conducting material

will not be required, as the water in the jacket 16 will prevent the burning up of the interior shell of the smoke-box. ²⁵

Having described my invention, what I claim is—

A locomotive smoke-box having its periphery provided with air-inlets, through which air is admitted to assist in the combustion of 30 cinders, said smoke-box provided with two concentric exhaust-pipes communicating with the engine-cylinders and having separate and independent nozzles which terminate in open mouths on the same horizontal plane, whereby 35 a uniform draft is maintained, substantially as described.

In testimony whereof I have hereunto set my hand.

FREDERICK GANDY.
